Patented Nov. 16, 1915.

UNITED STATES PATENT OFFICE.

ELLIOTT M. STORY, OF BROCKTON, MASSACHUSETTS.

COIN-CONTROLLED VENDING-MACHINE.

1,160,548.

Specification of Letters Patent. Patented Nov. 16, 1915.

Application filed January 13, 1915. Serial No. 2,046.

To all whom it may concern:

Be it known that I, ELLIOTT M. STORY, a citizen of the United States, and resident of Brockton, in the county of Plymouth and State of Massachusetts, have invented certain new and useful Improvements in Coin-Controlled Vending-Machines, of which the following is a specification.

This invention relates to coin-controlled machines for vending articles of merchandise, such as balls of chewing gum, loosely assembled in a reservoir and adapted to gravitate therefrom to a point of delivery.

The invention has for its object to provide simple and effective coin-controlled ejector mechanism for governing the release of articles one at a time from the reservoir.

The invention consists in the improvements which I will now proceed to describe and claim.

Of the accompanying drawings forming a part of this specification: Figure 1 represents a vertical sectional view of a vending machine embodying my invention, parts not necessary to illustrate the invention being broken away; Figs. 2, 3 and 4 represent views similar to portions of Fig. 1, showing different positions of the controlling gates hereinafter described; Fig. 5 represents a section on line 5—5 of Fig. 1, and a plan view of parts below said line; Fig. 6 represents a section on line 6—6 of Fig. 5; Fig. 7 represents a perspective view of the spring-pressed dog; Fig. 8 represents a side elevation of the complete machine on a reduced scale.

The same reference characters indicate the same or similar parts in all the views.

In the drawings 12 represents a hollow base forming a coin chamber which is covered by a top plate 13 forming the bottom of a chamber 14, which is located between the base 12 and the reservoir 15 in which the articles of merchandise 20 are stored. The reservoir is preferably a glass bowl detachably secured by suitable means, not shown, in an inverted position on a bottom piece 16 which forms the top wall of the chamber 14 and has a flange 17 forming the margin of said chamber and suitably secured to the base. The bottom piece or reservoir bottom 16 is provided with a relatively large central opening 18 forming the reservoir outlet. 19 represents a merchandise guide located in the chamber 14 and preferably composed

of a block having a passage 10 extending through it from top to bottom, the upper end of said passage being preferably flaring and the lower end contracted and adapted to permit the passage of only one article 20 at a time.

21 represents a slide which is normally held by springs 26 in a position retracted from the central portion of the chamber 14, as shown by Fig. 1, one end of said slide projecting from the exterior of the machine and constituting a push-piece whereby the slide may be projected into the chamber 14, as indicated by Figs. 2, 3 and 4.

With the slide 21 are connected two alternately operating gates 27 and 28, which are preferably parts of a sheet metal plate attached at one end by rivets 29 to the slide. The central portion of said plate has an enlargement 27^a, preferably of the same area as the guide 19, as indicated by Fig. 5, said portion being provided with an orifice 30 which normally coincides with the reservoir outlet 18, as shown by Fig. 1. The operative portion of the upper gate 27 is that extending between the orifice 30 and the body of the slide 21. The portion of the enlargement 27^a at the opposite side of the opening 30 and the neck 31 constitute a convenient means for mechanically connecting the gates 27 and 28, and causing said gates to move in unison. The plate enlargement 27^a is provided with ears 32 (Fig. 5), with which the gate-retracting springs 26 are connected.

When the slide 21 is retracted and held in its normal position by the springs 26 the upper gate 27 is fully open and uncovers the passage through the guide 19, the lower gate 28 at the same time covering and closing the lower end of said passage. The flaring upper end of the passage 10 is formed to permit spherical articles 20 to roll easily into the passageway, but prevents more than one article from wholly entering, the arrangement being such that when the slide 21 is projected the gate 27 will force its way through the mass of articles 20 and work under all the articles excepting the one wholly contained in the guide. When the slide is fully projected, as shown by Fig. 4, the upper gate 27 is closed to prevent the entrance of articles into the guide, and the lower gate 28 is open to permit the escape of a single article from the guide through a merchandise outlet 33 formed in the top plate 13. The guide 19, the slide 21, and

the gates 27 and 28 constitute an ejector in which my invention is embodied.

The coin-controlled means for preventing the projection of the ejector slide to the position shown by Fig. 4 includes a shoulder 34 formed on the upper edge of the slide 21, said shoulder being between the ends of a coin-receiving pocket 35 formed in said slide, and a spring-pressed dog 36 attached 10 to the reservoir bottom 16 and normally bearing yieldingly on the upper edge of the slide 21 at a distance from the shoulder 34 when the slide is retracted, as shown by Fig. 1. When there is no coin in the pocket 35 15 the dog 36 engages the shoulder 34 after a partial projection of the slide 21, as indicated by Fig. 2, the dog arresting the projecting movement of the slide before the lower gate 28 is open.

20 The machine is provided with a fixed coin chute 38 which registers with the coin pocket 35 when the slide is fully retracted, as shown by Fig. 1. The relative proportions of the slide, coin pocket, and chute are such that a 25 coin 37 adapted to enter the chute and pocket is deposited edgewise on a support or coin rest 39 forming a part of the top plate 13, one edge of the coin projecting above the slide 21 and being adapted to act as a cam 30 on the dog 36 when the slide 21 is projected. During the initial projection of the slide from the position shown by Fig. 1 to that 35 shown by Fig. 3 the dog 36 is continuously raised and held raised until the shoulder 34 passes by the engaging end of the dog. The slide is therefore free to be fully projected to the position to close the upper gate 27 and open the lower gate 28, the coin falling from the pocket 37 through a coin outlet 40 in the 40 top plate 13. The released article 20 falls through the outlet 33 in the top plate 13 and is conducted by a chute 41 to a tray 42 (Fig. 8) at the exterior of the base.

It will be seen that the retracting springs 45 26 act through the upper gate 27 to retract the slide 21, said springs being secured at 28^a (Fig. 5) to the top plate 13. The retraction of the gates and slide is limited by the guide 19, one end of which forms an 50 abutment for the neck 31.

The guide 19 is detachably secured in place by steady pins 43 attached to and projecting upwardly from the plate 13 and entering sockets 44 formed in the guide, as 55 shown by Fig. 6. The guide is loosely engaged with said pins and may be raised or upwardly displaced therefrom with the gates 27 and 28, this construction permitting the ready separation of the guide, the gates and 60 the slide from the machine when the reser-

voir bottom is removed and preventing horizontal displacement of the guide. The top plate 13 is provided with upwardly projecting ears 45 against which one edge of the guide 19 bears, said ears being at opposite 65 sides of the slide and guiding the latter in its movements.

The upper gate 27 is provided with means for agitating the articles 20 in the lower portion of the reservoir, said means as here 70 shown comprising two upwardly projecting pins 46 attached to the upper gate and projecting through the reservoir outlet 18. Said pins move across the reservoir outlet and among the adjacent articles 20 and prevent said articles from becoming clogged or wedged.

It is obvious that the machine may be used for delivering simultaneously a plurality of 80 separate articles, such as shelled peanut kernels, the guide 19, which may be called an open bottomed cup, being formed to contain a charge of kernels.

Having described my invention, I claim:

1. A vending machine comprising a reser- 85 voir having a merchandise outlet, a base sup- porting the reservoir and having a top plate, and an ejector including a merchandise guide located below and coinciding with said outlet, spring-controlled upper and lower 90 gates, one interposed between the guide and reservoir and the other between the guide and top plate, the said guide resting loosely on the lower gate, and a manually movable slide attached to and carrying said gates, 95 the said top plate being provided with guide-engaging means permitting the upward dis- placement of the guide and preventing its horizontal displacement.

2. A vending machine comprising a reser- 100 voir having a merchandise outlet, a base sup- porting the reservoir, and having a top plate provided with upwardly projecting steady pins, and an ejector including a mer- 105 chandise guide located below and coinciding with said outlet and provided with sockets receiving said pins, spring-controlled upper and lower gates, one interposed between the guide and reservoir and the other between the guide and base, and a manually movable 110 slide attached to and carrying said gates, the guide being detachably confined on the base by said steady pins and removable with the gates and slide.

In testimony whereof I have affixed my 115 signature, in presence of two witnesses.

ELLIOTT M. STORY.
